UNITED STATES PATENT OFFICE.

EDWIN L. TEVIS, OF PHILADELPHIA, PA., ASSIGNOR OF SEVEN-TENTHS TO
JAMES N. WHELEN, OF SAME PLACE.

SAFETY-GATE FOR CAR-PLATFORMS.

SPECIFICATION forming part of Letters Patent No. 289,726, dated December 4, 1883.

Application filed October 18, 1883. (No model.)

To all whom it may concern:

Be it known that I, EDWIN L. TEVIS, a citizen of the United States, and a resident of Philadelphia, Pennsylvania, have invented certain 5 Improvements in Safety-Gates for Railroad-Car Platforms, of which the following is a specification.

My invention relates to improvements in the construction of safety-gates for the platform 10 and platform-steps of a railway-car; and the main object of my improvements, which are fully described hereinafter, is to so construct and so place a gate that when raised it will present a proper safety-guard, and when depressed will be entirely out of the way, so as 15 to present no obstacle to free access to and exit from the car.

In the accompanying drawings, Figure 1 is a perspective view of part of the end of a car, 20 showing the guard in an elevated position; Fig. 2, the same, showing the guard depressed; Fig. 3, a front view of the guard, with mechanism which may be used for operating the same; Fig. 4, a section on the line 1 2, Fig. 3; 25 and Fig. 5, a diagram illustrating the manner of arranging the guard.

The guard or gate, which will be best understood by reference to Fig. 3, consists of the base A, preferably composed of two bars of 30 wrought-iron secured together in such a manner that there shall be a space between them, two vertical guide-rods, D D', the top rail, B, arranged to slide on the said guides, and two sets, E E', of levers, constructed in the well-known lazy-tongs fashion, for connecting the base A to the sliding rail B, the lowest pair, a a', of each set of lazy-tongs levers being pivoted by a pin, x, to the base A, and the highest pair of each set being connected by links 35 e e' to an attachment on the under side of the rail B.

It may be remarked here that, although I have shown two sets of lazy-tongs connections, there may be but one set or more than two sets.

45 In applying this guard or gate I remove that portion, w, of the platform at each edge of the same which overhangs the riser y, as shown in Fig. 5, and the guard is so adjusted to the front of the riser that the rail B of the guard 50 will, when depressed, be in the position occupied by the said projecting portion w of the

platform prior to its removal, so that the depressed guard cannot interfere with free egress from and free access to the car.

The base-bar A is secured to the steps of the 55 car in any suitable manner, and the lower ends of the guide-rods D D' are preferably secured to the base-bar, the upper end of the guide-rod D' being attached to the usual guard-rail of the platform, and the upper end of the guide-rod 60 D to the end of the car.

Different devices for raising and lowering the guard may be adopted. In the present instance the lowest pair of levers of one set are connected by links m m to one end of a bar, 65 M, the opposite end of which is connected to the lowest pair of the other set of levers by similar links. A short shaft, H, is arranged to bear in a hanger, t, on the under side of the platform, and an arm, n, on this shaft is connected by a link, p, to the bar M, an operating-lever, I, also secured to the shaft, passing upward through a slot in the platform. When the guard is depressed, the operating-lever is 70 in an out-of-the-way position against the usual guard-rail; but when the guard is elevated the lever occupies the inclined position shown in Fig. 3, where it may be temporarily held by any suitable retainer, so as to maintain the 75 guard in an elevated position.

It will be seen that there is a slot in the step w' adjoining the riser y, Fig. 5, for admitting and permitting the free movement of portions of the lowest of the two sets of levers, the links m and bar M being below this step.

The guard or gate may be placed on the inner side of the riser y, Fig. 5, in which case the platform will be slotted for the passage of the guard, the top of the rail B of the latter, when depressed, being level with the top of 90 the platform. I, however, prefer to arrange the guard in front of the riser, in which case, however, a suitable cover-plate—such, for instance, as shown by dotted lines in Fig. 4—may be placed in front of the guard.

95 I am aware that a gate composed of a system of lazy-tongs levers has been applied to the side of a car so as to close a platform. This, therefore, I do not claim, broadly; but

I claim as my invention—

100 1. The combination of the platform and platform-steps of a railway-car with the vertical

guides D D', the base A, sliding rail B, and lazy-tongs connections, substantially as set forth.

2. The combination of the system of lazy-tongs levers and bars forming a safety-gate with the operating-lever I, the shaft H, having an arm, n, and the bar M, connected to the said system of levers and to the bar n, as set forth.
- 10 3. The within-described safety-gate, the same comprising the base A, the opposite guides,

D D', the sliding rail B, and lazy-tongs connections between said rail and the base, as set forth.

In testimony whereof I have signed my name 15 to this specification in the presence of two subscribing witnesses.

EDWIN L. TEVIS.
